UNITED STATES PATENT OFFICE.

ATTILIO FRANCO, OF MILAN, ITALY.

STEAM GENERATOR.

Application filed February 11, 1925, Serial No. 8,590, and in Italy February 11, 1924.

The present invention has for its subject matter a novel type of boiler fitted with a longitudinally fired furnace, the furnace being of the ordinary type but having connected to it two banks of fire tubes facing one another. By the word "furnace" as used hereinafter is meant the aggregate made up by the furnace proper and by its shell.

10 The novel type of boiler is advantageous in those cases, for instance, where owing to restricted room conditions the space available for the boiler and for the furnace service is a limited one.

15 In the accompanying drawings several embodiments of the invention are illustrated by way of example.

Fig. 1 is a plan showing a boiler with two banks of fire tubes arranged in the form of 20 a symmetrical double T.

Fig. 2 is a cross section along 2—2 of Fig. 1 with the assumption that the boiler shell is circular in cross section.

Fig. 3 is a similar cross section along 2—2 25 of Fig. 1 but with the assumption of a boiler shell of oval cross section.

Figures 4 and 5 are vertical and horizontal sections respectively illustrating in detail a boiler with flattened sides.

30 Figures 6, 7 and 8 are plans illustrating several types of boilers, in which the longitudinal center lines of the two banks of fire tubes are either coincident with the center line of the boiler as Fig. 6 or staggered relative thereto as in Figs. 7 and 8; these figures also show different leadings of the furnace walls.

Fig. 9 is a plan showing the arrangement of the locomotive's cabin; it also shows the 40 boiler in horizontal section with the longitudinal center lines of the two banks of fire tubes staggered by a certain amount relative to the boiler's longitudinal center line.

Fig. 10 is a vertical section of the said cabin in connection with a boiler in which the cross section of the banks of fire tubes shows flattened sides.

Figures 11 and 12 are analogous figures to the two preceding figures and illustrate in plan and cross section respectively a locomotive's cabin in the case of a boiler in which the longitudinal center lines of the two banks of fire tubes coincide with the longitudinal center line of the locomotive and 50 of the cabin.

Figures 13, 14 and 15 are plans and show several constructions in which the longitudinal center lines of the banks of fire tubes do not coincide with the center line of the boiler and in which the two internal furnace 60 walls show different arrangements.

Fig. 16 is a section through 16—16 of Fig. 14 with the assumption that the two internal walls of the furnace close on each other above the grate.

Fig. 17 is a similar section through 16—16 in Fig. 14, with the assumption that the two said internal walls close on each other at furnace level.

Fig. 18 is a section through 18—18 in Fig. 15 with water tubes instead of the two aforementioned internal furnace walls.

Figs. 19 and 20 show the locomotive cabin in plan, the boiler being differently arranged in the two figures.

In Fig. 1, 1 is the metal furnace, 2 the furnace wall and 3 the furnace shell.

The straight lines *a*—*a* and *b*—*b* are the cross and longitudinal center lines respectively of the boiler.

The furnace 1, to which both banks of fire tubes 4 and 5 with their fire tubes 6 and 7 respectively are connected, has its cross headers 8 and 9 extended a sufficient distance to the two sides to provide for coal firing doors 10. According to requirements, these firing doors may be reduced to a single one, or several of them may be provided, for instance four as shown on Fig. 1. Further, the headers 8 and 9 may be at right angles 85 to the horizontal generating lines of the two banks of fire tubes 4 and 5 as shown for instance on Fig. 1, or they may lie at different angles relatively to the said generating lines as shown for instance in Figures 6, 7 and 8. 90

The banks of fire tubes may be cylindrical in section as shown on Fig. 2, or their cross section may exhibit flattened sides as per Fig. 3.

In the latter case the irregular form of the flat or approximately flat sides of the banks of fire tubes 4 and 5 can be obtained either by means of the ordinary stays or by means of special stays 11, that are shown in elevation in Fig. 4 and in plan in Fig. 5. 100

The ends of the stays 11 are secured by means of bolts 12, to the forks 13 riveted to the shell of the banks 4 and 5. As may be seen from Fig. 4, the stays 11 have circular apertures 14 formed in them of sufficient 105

diameter to permit the erection of the fire tubes as well as the passage of the water around the latter.

The banks 4 and 5 may be connected to the crossheaders 8 and 9 by means of the furnace shell in such a manner that the projections 15 and 16 of their longitudinal centre lines coincide with the straight line $c-c$, viz with the longitudinal center line 10 of the boiler, or the said projections 15 and 16 may not coincide with $c-c$ and lie at a certain distance from it.

Figures 9, 10, 11, and 12 illustrate by way of example the application of a boiler to a 15 locomotive, with banks of fire tubes either coaxial with the boiler as in Figs. 11 and 12 or non coaxial as in Figs. 9 and 10.

The surfaces 19, 20, 21, 22, 23, and 24 with lozenge hatching give an idea of the 20 cabin space available for the fireman for firing the boiler and handling the firing tools.

The surfaces 25, 26, 27, 28, 29, and 30 give an idea of the space available for the 25 coal bunkers; suitably inclined planes cause the coal to descend by itself within reach of the man's shovel without the man being obliged to turn himself in order to fill the shovel with coal.

As compared with the boilers used heretofore, the novel locomotive boiler secures 30 the following advantages:

1. Boilers with large heating surface and large gas passage sections can be installed in locomotives where only a restricted space 35 is available for them; besides, more than one man can be employed for the firing, each man having considerable space at his disposal for the fire service. The men can therefore keep the air passages between the gratebars 40 clean from slag, the checking of such passages notoriously being one of the main causes limiting the time periods during which the locomotive can be kept in service, the men not being able to simultaneously 45 perform the double duty of maintaining the furnace well fed with coal and keeping the grate properly clean.

2. Suitable accommodation is provided for the 50 firing tools alongside the shell of the banks of fire tubes. These tools can be supported and balanced along the cabin by means of a suitable movable rest; accordingly heavier tools which are less liable to be impaired by fire can be employed without undue exertion and fatigue on the part of the fireman, such tools being more fit than those used at 55 present to overcome the resistance that is often met with in the removal of slag.

3. The stoker has the coal within easy 60 reach of his shovel, whereas in the present locomotives he is obliged to turn himself in order to fill the shovel with coal.

The modifications according to Figs. 13 65 to 20 relate to the furnace proper and has for its object the increase of the heating

surface of the furnace as well as the water circulation in the boiler by providing water tubes arranged in the furnace or by providing two internal walls in the furnace, in the direction of the boiler's longitudinal center 70 lines, the said two walls dividing, or not dividing the furnace capacity into two separate chambers according as the said internal walls close on each other at grate level or above grate level. In the former case, that is where the walls close on each other at 75 grate level, the furnace remains common to the two banks of fire tubes as far as the water contained in said banks is concerned; in the latter case, that is where the walls close on 80 each other above grate level, as well as in the case of the abovesaid water tubes being fitted, the furnace remains common to the two banks of fire tubes both as regards the hot gases and as regards the water contained in the two banks.

In Figures 13, 14, and 15, 31 is the boiler furnace comprising the furnace proper and its shell; 32 are the perimetral cross walls of the furnace; 33 are the perimetral longitudinal walls of the furnace; 34 is the furnace envelope or shell; 35 are the fire-doors arranged sideways of the banks of fire tubes for the longitudinal firing of the 90 boiler.

36 are the furnace inside walls (Figures 13 and 14) built into the end wall 32 and forming an additional heating surface as well as a longitudinal water canal by which the water space of one bank is set into communication with the water space of the other bank.

In Fig. 13 the inside walls 36 are shown parallel to the longitudinal center line $a'-a'$ of the boiler.

In Fig. 14 the inside walls 36 are shown inclined relative to the said center line $a'-a'$. The wall arrangement according to Figures 13 and 14 is merely given by way of example.

Figs. 15 and 18 are a plan and vertical section respectively showing by way of example a collector 37 of any desired shape (for instance D-shaped) built into the furnace cross walls 32 at grate level. The bottom end 38 of the vertical watertubes 39 is 110 expanded into the collector 37, while their top end 40 is expanded into the furnace ceiling.

Figures 16 and 17 are both vertical sections on line 16-16 of Fig. 14, the former 120 one in the case of the furnace walls 36 closing on each other at a distance $-b-$ above the grate level, and the latter one in the case of the walls 36 reaching down to the level of the grate-supporting frame like the walls 33 125 and 34.

42, and 43 in Figures 19 and 20 are the outlines in plan that cannot be exceeded according to the railways' loading gauge.

$c'-c'$ and $d-d$ in Figures 19 and 20 are 130

the cross and longitudinal center lines respectively of the locomotive; $e-e$ are the longitudinal center lines of the banks of fire tubes; 44 are the firedoors arranged sideways of 5 said banks for the longitudinal firing of the boiler.

In Fig. 19 the cross and longitudinal center lines of the boiler coincide with $c'-c'$ and $d-d$ respectively.

10. In Fig. 20 the boiler is so arranged that its cross center line $f'-f'$ and its longitudinal center line $g-g$ lie at a certain angle $-h-$, in horizontal plane, with the locomotive center lines $c'-c'$ and $d-d$ respectively.

15. Having now described and ascertained the nature of my invention and in what manner the same is to be performed, I declare that what I claim is:

1. A boiler comprising, a central furnace 20 provided with cross walls, and a bank of fire tubes mounted in either cross wall of said furnace and extending parallel to the boiler axis, said furnace cross walls having portions projecting laterally of said tube banks, said portions provided with openings for longitudinal firing.

2. A boiler comprising, a central furnace 30 provided with cross walls, and a bank of fire tubes mounted in either cross wall of said furnace and extending parallel to the boiler axis, said furnace being divided into separate combustion chambers by a substantially longitudinally extending partition wall.

35. 3. A boiler comprising, a central furnace provided with cross walls, and a bank of fire tubes mounted in either cross wall of said furnace and extending parallel to the boiler axis, the water space of said tube banks being

joined by a water wall extending substantially longitudinally through the combustion chamber. 40

4. A boiler comprising, a central furnace provided with cross walls, and a bank of fire tubes mounted in either cross wall of said furnace and extending parallel to the boiler 45 axis, said furnace being divided into separate combustion chambers by a longitudinally extending partition wall, said furnace cross walls having portions projecting laterally of said tube banks, said portions provided 50 with openings for longitudinal firing.

5. A boiler comprising, a central furnace provided with cross walls, and a bank of fire tubes mounted in either cross wall of said furnace parallel to and laterally displaced 55 from the center line of said boiler, said furnace being divided into separate combustion chambers by a longitudinally extending partition wall, said furnace cross walls having portions projecting laterally of said tube 60 banks, said portions provided with openings for longitudinal firing.

6. A boiler comprising, a central furnace provided with cross walls, and a bank of fire tubes mounted in either cross wall of said furnace, said banks of fire tubes being laterally offset, said furnace being divided into separate combustion chambers by a longitudinally extending water wall connecting the water space of said tube banks, said furnace cross walls having portions projecting laterally of said tube banks, said portions provided with openings for longitudinal firing, each of said openings being in alinement with one of said banks of fire tubes. 70

ATTILIO FRANCO.
